FIG. 2.

INVENTOR.
Frederick L. G. Straubel

UNITED STATES PATENT OFFICE

1,929,612

FILING CABINET OR FILE BOX

Frederick L. G. Straubel, Green Bay, Wis., assignor of one-eighth to O. C. Straubel, Green Bay, Wis., and two-eighths to C. W. Straubel, Youngstown, Ohio

Application August 12, 1932. Serial No. 628,525

12 Claims. (Cl. 129—16)

The invention relates to filing cabinets or file boxes of the kind with hinged top covers whereby the contents of the file may be exposed for better examination or access thereto.

- 5 This application is supplementary to my application No. 561,650, filed September 8, 1931, Patent #1,892,476, December 27, 1932, but with a rearrangement of operating devices and a change in the method of hinging the cover.
- 10 As in my application of Sept. 8, 1931, this invention also contemplates means in connection with the hinged cover wherewith the rear end of an inner filing receptacle is raised sufficiently to improve the vision of the user in looking for 15 the desired indexes or for the examination of papers filed therein. The mechanical operation however, differs in that it has a more positive connection directly from the lifting device for the outward tilting of the front and bringing it back 20 to a normal position. The hinges of the cover are attached to the back of the outer casing and to a slide on the inside of the cover that will permit the cover to be dropped down back of the casing and simultaneously operate the lifting 25 and tilting devices. For convenient and quick access to the contents of the file, it is merely necessary to open the cover when automatically the rear end of the inner filing receptacle is raised by means of the connections hereinafter 30 described, and the closing of the cover will return the inner file to its normal position as also the tilting front.

With this object in view my invention consists in construction and operation substantially as described and set forth in the accompanying drawings.

Figure 1 is a longitudinal sectional view through the center of the file or cabinet.

Figure 2 is a cross-section from center to outside viewed from the rear end of the casing with its back partly cut away.

Figure 3 shows the style of hinge used for the tilting front and inner file or receptacle.

Figure 4 is a perspective view of the cover hinge and slide. Only one side of the file is shown in Figures 1 and 2, the opposite side having the same mechanical devices in reversed positions. The same numerals are used to indicate the various parts. In the drawings 1 is the cover and 2 the side of the outer casing. 3 is the outwardly tilting front, 4 the back of the outer casing and 5 its bottom. 6 the inner side of the filing receptacle and 7 its bottom. 1 to 7 constitute the major portions of the cabinet or file box which may be subject to a variety of designs and of suitable

material, preferably steel. 16 is an inwardly projecting wing attached to the tilting front 3 adjacent to the inner side 6 of the filing receptacle. 18 is a front throwback or compressor pivotally attached at its lower extremity to the 60 side 6 at 19. 21 is a rearwardly inclining follower hinged to its base 22 at 23 and movable for adjustment of the contents filed, from near the front to the rear of the inner file, by means of its forwardly extending shoe 30 to slide within 65 the runway 26 attached to the lower part of the side 6.

The hinging of the cover 1 differs from that described in my application No. 561,650, in having the lower part of the hinge 31 attached to the 70 back of the casing at 8 and its upper part to the slide 9 at 10. The slide 9 moves within the scope of the runways 11—11 in the side of the cover, providing means whereby the cover 1 may be moved upward with a swinging movement and 75 downward, back of the casing as shown by dotted lines in Figure 1. As a means for lifting the rear end of the inner file receptacle, the rod or lever 12 is pivotally attached to the inner file at 13 and its upper end to the slide 9 at 29. Pivotally attached to the lifting rod 12, at its lower extremity, is the rod or link 15, which is pivotally attached to the wing 16 or 17. By the opening of the cover 1 the rods 12 and 15 assume the positions shown by dotted lines in Figure 1, thereby raising the 85 rear end of the inner file and forcing the front 3 to an outward tilted position, also shown by dotted lines.

In the drawings these operating parts are shown to be on the inner side of the inner file 90 receptacle, protected against interference with the contents of the file by the inwardly extending roll 35 along the top of the side 6 and the inward formation 36 of the follower slide 26, attached to the side 6 at its bottom part. The 95 arrangement shown can be changed to have the lever 12 and link 15 on the outer side of the inner file with the link 15 protruding through an opening at or near the wing 16 for attachment thereto.

In the open position of the file the indexing and papers filed will be in an inclined position at the top for a better view of those rearwardly elevated. The compressor or throwback 18, which is pivotally connected at its lower extremity at 19 to the side 6 and above that being in contact with the tilting front at 20, because of its formation which extends to the opposite side of the file in the form of a bail, lays flat against the inner side of the front 3 when the latter is 110

tilted outward, as shown by dotted lines. When the file is being closed the compressor will force the contents of the file backward parallel with the backwardly inclining follower.

5 The movable follower 21 is hinged to its base 22 at 23 and supported for the desired inclination by the side piece 24, which may be adjustably attached as shown in Figure 2, to regulate the incline.

10 The projection 25 on the follower is to prevent the contents, when the file is filled to capacity, coming in contact with the back of casing when the file is being closed, the projection coming in contact with the back to partly tilt the follower forward. 28 is a rest for the support of the rear end of the inner file when in normal position and the slotted connection 29 to the slide 9 will compensate for any variation between the rest 28 and the closed cover 1 and also provide 20 for the cover to partly raise before operating the lifting rod 12 to raise the inner file.

Figure 3 shows a preferred style of continuous hinge adapted for the hinging of the front end of the inner file receptacle and the tilting front, the upper flaps 32 to be attached to the front 3 and those laterally extended to the bottom 7 of the inner file and the lower part 34 of the hinge to the bottom 5 of the outer casing. Figure 4 shows a method of combining the hinge 31 with the slide 9 which is attached to it by a right angular flange 10.

Having thus described my invention that which I claim to be new and desire to secure by Letters Patent is—

35 1. A filing cabinet comprising an outer casing, an inner filing receptacle hinged at its front end to the bottom of the casing, a tilting front member, a cover, a slide connected with the cover, and pivoted means for attaching the slide 40 to the outer casing for a swinging and downward sliding movement of the cover.

2. A filing cabinet comprising an outer casing, an inner filing receptacle hinged at its front end to the bottom of the casing, a tilting front 45 member, a cover, a slide connected with the cover, means for attaching the slide to the outer casing for a swinging and downward sliding movement of the cover, and means connected with said slide for raising the rear end of the inner filing 50 receptacle by the opening of the cover.

3. In a filing cabinet, an outer casing including side, back and bottom walls, a tilting front, and a cover; means for pivotally and slidably mounting said cover on the outer casing, an 55 inner tiltably mounted filing receptacle, and operating connections respectively between the cover, the tiltably mounted inner receptacle and tilting front.

4. In a filing cabinet, an outer casing including hinged top and front walls, an inner tiltably mounted filing receptacle, a lever pivotally connected at its intermediate portion with the inner tiltably receptacle and having one end thereof pivotally connected with the cover, and 65 a link pivotally connected with the end of said lever opposite the end connected with the cover, and the other end of said link being pivotally connected with the hinged front wall.

5. In a filing cabinet, an outer casing including 70 a hinged top and a hinged front, an inner receptacle tiltably mounted within the outer casing, a lever fulcrumed to the inner casing and having one end pivotally connected with the hinged cover, and a link pivotally connecting the 75 lever with the hinged front.

6. In a filing cabinet, an outer casing including a cover and a tilting front, means for slidably and pivotally mounting the cover on the outer casing, an inner casing tiltably mounted within the outer casing, a lever fulcrumed to the inner casing and having one end operatively connected with said means for slidably and pivotally connecting the cover with the outer casing, and a link connecting said lever with the tilting front.

7. In a filing cabinet of the class described, an outer casing including a tilting front, an inner casing tiltably mounted within the outer casing, a cover for the outer casing, and operating connections between the cover, the inner casing, and the tilting front whereby the lifting of the cover lifts the inner casing and moves the tilting front outwardly.

8. In a filing cabinet, an outer casing including a tilting front, a tilttable inner receptacle, a cover, means for pivotally and slidably mounting the cover on the outer casing, a lever fulcrumed to the inner receptacle and having one end connected to said means, a link operatively connecting said lever with the tilting front, a compressor for the inner receptacle comprising a member 100 pivotally mounted at its lower end to the receptacle and controlled in its movement by the tilting front.

9. In a filing cabinet of the class described, an outer casing including a hinged top and a tilting front 105 operatively connected whereby movement of the cover controls the tilting front, a tilttable inner receptacle operatively connected with the cover to be lifted at one end, a compressor pivotally mounted in the receptacle and controlled 110 by the movement of the tilting front, and a follower within the inner receptacle, said follower being pivotally and slidably mounted in the receptacle and having an inclination corresponding substantially to the angle of inclination of the 115 compressor.

10. In a filing cabinet, an outer casing including a tilting front wall, an inner tilttable receptacle, a hinge unit carried by the casing, a cover 120 slidably connected with said hinge unit, means operatively connecting said hinge unit, the inner tilttable receptacle and the tilting front, whereby movement of the cover actuates said receptacle and front.

11. In a filing cabinet, an outer casing, a tilting 125 front, an inner tilttable receptacle, a cover, mounting means for hingedly and slidably supporting the cover on the outer casing, an operating connections between the said mounting means, receptacle and tilting front whereby when the cover 130 is raised the operating connections will tilt the front outwardly and lift the inner receptacle and the cover will slide downwardly at the rear of the casing.

12. In a filing cabinet of the class described, 135 the combination with a tilting front and a tilttable inner receptacle and a cover, of mounting means for supporting the cover on the cabinet to permit pivotal and sliding movement of the cover with reference to the cabinet, and operating 140 connections between said mounting means, receptacle, and tilting front, whereby said cover in its open position will be disposed substantially parallel with one of the sides of the cabinet and constitute means to prevent accidental inward 145 movement of the tilting front.

FREDERICK L. G. STRAUBEL.
